UNITED STATES PATENT OFFICE

2,555,870

KNITTING MACHINE

Paul W. Bristow, Laconia, N. H., assignor to Scott & Williams, Incorporated, Laconia, N. H., a corporation of Massachusetts

Application December 18, 1945, Serial No. 635,644

39 Claims. (Cl. 66—14)

1

This invention relates to a knitting method and machine, and has particular reference to the type of machine comprising superposed needle cylinders and means for effecting panel wrapping therein, although it will be understood that certain features of the invention are not limited to this type of machine.

One of the general objects of the present invention is the provision of an improved wrapping mechanism involving the handling of wrap yarns so as to secure better plating of the wrap yarns in the fabric. In connection with this object of the invention, an improved construction of wrap head is provided, including, among other features, the provision of a dial for properly locating the lower ends of wrap fingers which carry the wrap yarns across the needle circle.

A further object of the invention is concerned with the mounting of the wrap head so that the wrap yarn fingers or carriers may be withdrawn from an upper needle cylinder and located in a convenient position for threading, while at the same time there is insured rigidity of construction and proper location of the wrap yarn carriers when they are returned to their active positions. To improve the nature of the wrapping, an improved stationary wrap horn is provided carried by a stationary sleeve within the upper needle cylinder.

For the purpose of providing improved interlacing in the formation of wrapped designs, the upper needle cylinder is provided with movable walls arranged to cooperate with the wrap yarns in the wrapping operation to insure that those needles which do not take the yarns will pass outwardly of the yarns in the interlacing action.

Besides the movable walls functioning as above, there are provided other movable walls which carry verge bits for the purpose of cooperating with the needles knitting in the upper cylinder in forming loops.

These and other objects of the invention, particularly relating to details of construction and operation, will become apparent from the following description, read in conjunction with the accompanying drawings, in which:

Figure 1 is a partial front elevation of a machine embodying the subject-matter of the invention;

Figure 2 is a partial vertical section of the machine showing in particular the actuating means for the pusher for acting upon the heel and toe pockets;

Figure 3 is an axial section illustrating particularly the wrap head;

2

Figure 4 is a fragmentary elevation of the lower end of a wrap yarn guide and the means for maintaining its normal position when it is inactive;

5 Figure 5 is a view showing in plan the means for positioning the lower end of a wrap yarn guide, one of which is illustrated in section;

Figure 6 is an axial section showing the needles and the parts in the vicinity thereof and directly 10 cooperating therewith;

Figure 7 is an elevation showing in particular the wrap head and the manner in which it is raised and positioned for threading;

Figure 8 is a perspective view showing the 15 means for latching the heel and toe pocket pusher in inactive position;

Figure 9 is a plan view of the same;

Figure 10 is a vertical section through the same;

Figure 11 is a fragmentary sectional view 20 illustrating the means for aligning the wrap head assembly;

Figure 12 is a diagrammatic perspective view showing in particular the needle selecting means and the wrap yarn guide controlling means;

25 Figure 13 is a plan view, partially broken away, of the wrap yarn guide controlling means;

Figure 14 is a horizontal section showing the needle selecting means;

Figure 15 is a perspective view showing a needle 30 jack and the cams for selecting the same;

Figure 16 is a fragmentary elevation of the needle selecting means;

Figure 17 is a perspective view of the same;

Figure 18 is a fragmentary elevation of the 35 same;

Figures 19 and 20 are elevations of the controlling cams for the needle selecting means;

Figure 21 is an elevation of a stocking produced by the machine;

40 Figure 22 is a perspective view showing in particular the abutment for the wrap yarn guide and the lowering pick and the means for controlling the same;

Figure 23 is a fragmentary plan view showing 45 the yielding action of the abutment;

Figure 24 is a perspective view illustrating the beginning of a wrapping operation and the initial engagement of a wrap yarn guide with the abutment;

50 Figure 25 is a fragmentary plan view of the same event;

Figure 26 is a perspective view similar to Figure 24 but showing a later event in the needle wrapping operation;

Figure 27 is a fragmentary plan view of the last mentioned matter;

Figure 28 is a further view similar to Figure 24 but showing the completion of a needle wrapping operation;

Figure 29 is a fragmentary plan view of the parts in the condition of Figure 28;

Figure 30 is a perspective view and Figure 31 is an elevation, partly broken away, of certain elements cooperating with the wrap yarns and the fabric;

Figures 32 to 36, inclusive, are perspective views illustrating the functions of the elements of Figures 30 and 31;

Figure 37 is a diagrammatic view illustrating controlling means for the lowering picker;

Figures 38 and 39 are further perspective views of the same;

Figure 40 is a perspective sectional view of the pusher for the heel and toe pockets illustrating its action;

Figure 41 is a section showing the form of the pusher;

Figures 42 and 43 are diagrams illustrating certain pattern formations achieved by the machine;

Figure 44 is a developed view of the cams looking, in general, outwardly from the axis of rotation, and showing at the right thereof a needle and cooperating elements;

Figures 45 to 49, inclusive, are developed views of the needle controlling cams looking outwardly from the axis of rotation of the cylinders;

Figure 50 is a diagrammatic plan view showing the sinker movements in the machine; and

Figure 51 is a partial development of the sinker cams.

The knitting machine embodying the inventions indicated above is of the superposed cylinder type comprising a lower cylinder 2 and an upper cylinder 3. Arranged to slide in slots in the lower cylinder are sliders 4 adapted to engage the lower hooks of double hook latch needles 6, the upper hooks of which are engageable by sliders 8 in the upper cylinder.

The lower sliders 4 are provided with butts at two levels 16 and 12 as hereafter more fully described and, in addition, with saw tooth butts 14 arranged to provide for selection by suitable cams. The upper sliders 8 are provided with butts at two levels 16 and 18. The cylinders are preferably provided with inserted fixed walls to define the slots for reception of the sliders and these walls 20 in the case of the upper cylinder terminate substantially above its lower end so that the lower portions of the slider slots are bounded not by stationary walls but by movable walls or two alternative forms arranged to slide in the wall slots in the upper cylinder. One set of these indicated at 22 carries butts 26 (see Figure 32) and are provided with outwardly and downwardly sloping lower ends as indicated most clearly at 30 in Figure 24. The other slidable walls indicated at 24 are provided with butts 28 and have verge bit extensions such as indicated at 32 in Figure 24. The arrangement and functions of these lower ends 30 and the verge bits 32 will be hereafter described. The verge bits are located between the positions of needles which, in the formation of broad ribs, are located in the upper cylinder.

The cylinders are rotated in unison through the medium of a vertical shaft 34 which, through gearing indicated at 36 (Figure 2), is driven by

the lower cylinder and which, through gearing indicated at 40 and 42, drives the upper cylinder. The present machine additionally involves the driving of a wrapping assembly which is effected through gears 44 and 46, the former being carried by the shaft 34.

Arranged to cooperate with the needles are arcuate sinkers 48 which are provided with butts 50 arranged to be acted upon by stationary cams 52 and 53 (see Figures 6 and 51) supported by a stationary cylinder 54 inside the lower rotating cylinder. This stationary cylinder 54 also supports the fabric guiding tube 56.

The rotary support for the wrap yarn carrying means is indicated generally at 58 (Figure 3). It is secured to the gear 46 and includes a member provided with an annular groove 60, in which groove are receivable the rounded pivot-forming projections 62 of wrap yarn carriers 64 surrounded by a spring band 66. Each of the wrap yarn carriers 64 has an upper extension 68 receivable in a notch 70 in an individual slider 72. These sliders 72 are provided with slots arranged so that they may embrace an annular ring 74 carried by the support 58. In order to guide the sliders 72 for radial movement and to position them in fixed circumferential locations they are received in slots 76 in the support 58. Each of the sliders is provided with a plurality of butts 78 indicated in the present instance as three in number. As will be evident hereafter, these butts may be selectively broken away so as to provide selection in the operation of the wrap yarn carriers.

Each of the wrap yarn carriers 64 is provided with a downward extension 78 extending through the upper cylinder and guided at its upper end in a radial slot 80 in the support 58. Individual springs 82 serve to urge the lower ends of the wrap yarn carriers inwardly. Butts 84 are provided on the wrap yarn guides to provide for the positive inward movements of their lower ends.

At its lower end each wrap yarn carrier is provided with a radially directed extension 86 which has a downwardly extending branch 87 provided with the yarn guiding openings 88. The downwardly extending branches 87 are provided with smooth lower inner edge portions arranged to cam the wrap yarn downwardly as the wrap yarn finger or carrier is withdrawn inwardly following a wrapping movement. Beyond these openings each carrier is provided with an abutment-engaging extension 90.

A tube 92, the upper end of which is secured in the assembly 58, carries at its lower end a disc 94 which is provided with radial fins 96, the upper edges of which are turned, as indicated at 98, in a clockwise direction as viewed in the plan view constituting Figure 5. These edges 98 provide rests for the purpose of definitely positioning the lower ends of the warp yarn guides which are flexed in a counterclockwise direction as viewed in Figure 5 in order to insure normal engagement with these edges.

Extending downwardly within the upper cylinder 3 is a stationary cylinder 100, this being interposed between the cylinder 3 and the wrap yarn guides. The cylinder 100 is carried by a portion of the frame which supplies a lower bearing 101 for the rotating support 58.

An axially extending rod 102 is guided for lengthwise movement through the tube 92 and carries at its lower end a fabric take-up disc or pusher 104 provided with rounded fingers 106.

The rotating warp yarn carrying assembly in-

cludes a disc 108 on which are supported the wrap yarn bobbins 110, of which there is one for each wrap yarn, only one of these being illustrated in the interest of clarity in Figure 2. The wrap yarns pass from these bobbins through the individual tension devices indicated at 112 and take-up sweeps 114 and thence downwardly through openings 116 and 117 about the lower edge of the cylinder 100 (when the wrap yarn guides are outwardly projected) and through the eyes 88 in the individual wrap yarn carriers. The tension and take-up devices, which are of conventional type, are carried by a disc 115 secured to the disc 108 through the medium of a tube 119.

A stationary tube 118 carried by the machine frame, acts as a vertical guide for a post 120 slideable and rotatable therein, which post is provided with a collar 122 limiting its lowermost position by engagement with a collar 128 carried by the upper end of the tube 118. The collar 122 is provided with an extension 124 engageable within a notch in a block 126 carried by the collar 128 to fix the angular position of the post 120 when it is in its normal lowered location. The post 120 carries an arm 130 which is provided with an extension 132 provided with a conical member 134 arranged to be received in the upper end of a fixed tube 136. The arrangement just described provides a rigid mounting for an upper bearing 138 of the revolving warp yarn carrying assembly and serves to align the assembly with the lower bearing 101 when, as hereafter described, it is returned to an active position after being removed therefrom. Within the bearing 138 is a running collar 140 to which is secured a tube 142 which extends downwardly and is secured at its lower end to the lower portion of the wrap yarn carrying assembly. (See Figure 3.) Within the upper portion of the tube 142 is a cylindrical head 144 secured to the rod 102 previously mentioned. Pin 148 projects into a longitudinal slot 146 and so causes the head 144, the rod 102 and the take-up disc 104 to rotate with the wrap yarn assembly. When the rod 102 is in its uppermost position with respect to the assembly, with the disc 104 and the fingers 106 housed in the dished lower surface of the disc 94, a latch 152 controlled by a spring 154 and pivoted on the member 140 is arranged to enter an annular slot 150 near the upper end of the head 144. This latching of the rod 102 in its uppermost position is effected by hand operation when the warp assembly is to be removed from the upper cylinder; normally the rod 102 and the pusher are unlatched being automatically raised at the time of starting the broad rib in the leg and at the beginning of the ring toe, and being allowed to drop at the end of the heel and again at the end of the toe.

The upper end of the rod 102 is provided with a collar 156 and slidably arranged on the rod 102 is a collar 158, there being between these collars a cushioning spring 160 surrounding the rod 102. Arranged to act beneath the collar 158 is a lever 162 pivoted at 164 to a bracket carried by the post 120 and arranged to be acted on at a pivot pin 166 by a rod 168 connected to a lever 170 pivoted on the extension 124. The lever 170, when the parts are in normal operating position, overlies the upper end of a guided push rod 172 which is engageable by the head of an adjustable screw 174 carried by a bell crank 176 adapted to be acted upon by cams 178 and 180 on the main cam drum 182, the lowermost

position of the rod 172 being limited by a collar 173.

The wrap yarn supporting means just described is so arranged as to permit the entire wrap yarn assembly to be raised clear of the upper cylinder and swung to one side to permit threading of the wrap yarn carriers. By raising the entire assembly, i. e., by withdrawing the post 120 outwardly from the tube 118, the lower ends of the wrap yarn carriers may be brought clear of interfering parts of the mechanism as indicated in the upper dotted line position in Figure 7 and the assembly may then be swung to one side and lowered to the left hand dotted line position where easy access may be had to all of the parts of the wrap assembly. By reverse operations the assembly may be placed in its operating position into which it is accurately guided by engagement of the cone 134 in the upper end of the tube 136 and by engagement of the extension 124 in the notch in the block 126, which latter engagement, in particular, lines up the lever 170 with the push rod 172.

At the lower end of the stationary cylinder 100 there is carried by a bracket member 184 a wrap horn 186 which at its initial end is in the form of a horizontal strip and which, beyond the region of presentation of wrap yarns to the needles, is turned to a vertical position indicated at 188, this, as indicated hereafter, being to insure a high position of the wrap yarns on the needles as they are raised following wrapping. The trailing end of this horn is upwardly bevelled as indicated at 190 and overlaps a plating cam 192 also carried by the stationary cylinder 100. This plating cam is provided with a downwardly sloping forward edge 194 for the purpose of forcing downwardly a wrap yarn as hereafter described. Another function is to assist yarn take-up in tightening the wrap yarn when interlacing takes place. Immediately beyond this plating cam is a member 198 which is provided with flat fabric engaging members 198, 200 and 202. The function of these is to hold downwardly, in particular, heels and toes during the knitting operations and to assist the yarn take-up in control of the wrap yarn while stitches are being drawn during wrap patterning.

For the purpose of controlling the wrap yarn carriers there are provided cams 204 pivoted on the machine frame and arranged to cooperate with the butts 73 of the sliders 72 as hereafter described. These cams 204 are provided with tail portions 208 which are urged by individual springs 206 into engagement with cam projections 210 on slides 212, one of which corresponds to each of the cams 204. These slides 212 are urged in a rearward direction, as viewed in Figure 12, by individual springs 214 against the pull of Bowden wires 216 connected to vertical rods 218 which are acted upon by cams on the main cam drum 182 of the machine.

To provide positive return of the wrap yarn carriers following their projection of wrap yarns across the needle cylinders there are provided cams 222 arranged to act upon the butts 84. These cams act to return the wrap yarn carriers at slightly different times for the reasons given hereafter.

For the proper control of the wrap yarn carriers to cause them to wrap a possible plurality of needles in each operation, there is provided a yielding abutment shown at 224 engageable by the ends 80 of these carriers. This abutment 224 is carried by a shaft 226 extending downwardly through a stationary tube 228 secured at 230 to

the machine frame and carrying at its upper end a stop 232 which is adjustable for the accurate positioning of the abutment 224. At its lower end the shaft 226 carries an arm 234 which is acted upon by a tension spring 236 serving to maintain normally the abutment in contact with the stop 232. The spring 236 is fairly strong so that normally the abutment 224 presents a fixed stop for the wrap yarn carriers. In case of an accident, however, for example, engagement of a wrap yarn carrier with a needle, the abutment 224 may yield against the action of 236 to permit the wrap yarn carrier to pass without mechanical damage.

To serve for the control of the lower sliders 4 by engagement with their butts 14 there are provided cams 238 mounted for radial sliding movement with respect to the lower cylinder. Each of these cams is provided with a notch at its outer end engageable by an individual lever 242 of a stacked group, which levers are provided with follower ends 244 engageable with the butts of elements 246 mounted in a trick wheel 248, springs 250 serving to urge the levers 242 in a clockwise direction, as viewed in Figure 14. An upwardly projecting member 252 carried by a lever 253 urged clockwise, as viewed in Figure 14, by a spring 255 serves, under proper conditions, to move all of the levers 242 counterclockwise to withdraw the cams 238 outwardly irrespective of the butts of elements 246 which may be operatively related to their ends 244.

The trick wheel 248 carries a ratchet 254 arranged to be acted upon by a pawl in the form of a bar 256 having a hooked end. This bar 256 is pivoted at 260 to a lever 262 secured to a vertical shaft 263 which carries an arm 264 arranged to be acted upon by an adjustable screw 266 carried by one arm of a bell crank 268 pivoted at 270 and having its other arm provided with a follower roller 272 arranged to be acted upon by cam 274 rotating with the upper needle cylinder. By the action of this cam 274 and the connections just described, the trick wheel is advanced one step upon each rotation of the needle cylinders. A spring 276 urges the lever 262 clockwise, as viewed in Figure 14, while a light spring 278 acting on the bell crank 268 prevents disengagement of the screw 266 from the arm 264.

The pawl bar 256 carries a laterally extending plate 280 provided with a notch 282 in which is receivable a pin 284 carried by a lever 286 having a follower end 288 arranged to be acted upon by butts 290 at one level in the trick wheel. The series of butts 290 are continuous about the trick wheel except for one break provided for the purpose of timing. A Bowden wire 292 connects the lever 286 to a push rod 294 arranged to be acted upon at proper times by cams 296, 298 and 300, carried by the main cam drum 182. (See Figure 20.)

A Bowden wire 302 connects the lever 253 with a push rod 308 which is arranged to be acted upon by cams 304 and 306 on the cam drum 182. (See Figure 19.)

A lowering picker 310 is pivoted in the usual fashion to a vertical post arranged to oscillate about a vertical axis, the tail end of the picker being urged downwardly by a spring 311 so as to follow a double cam 312 during oscillatory movements of the supporting post upon engagement of the picker by a needle moving in either direction. The conventional spring controlled arrangement indicated at 314 normally maintains the picker in central position. A lever 316

pivoted underneath the tail of the picker carries a cam 318 arranged to act thereon when the lever is rocked against the action of the spring 320 by the Bowden wire 322 connected to a push rod 324 acted upon, through an intermediate cam follower lever, by a cam 326 on the main cam drum 182. When the cam 318 acts on the picker its active end is held depressed to proper level for picking down heel sliders.

In accordance with the present invention there is pivoted on a horizontal pin 330 an arm in the form of a bent stiff wire 328, which arm is normally urged inwardly in a direction toward the needle cylinder by a spring 332. A wire 334 carried by a vertical shaft 336 has a turned end embracing the lever 328. The upper end of the shaft 336 is provided with a cam following arm 338 adapted to be engaged during rotation of the needle cylinders by a cam 340 carried by the upper needle cylinder. The arrangement, the operation of which will be hereafter described, is such that when the picker is operated so that its tail is raised the wire lever 328 which normally rests against the tail will drop beneath the same, holding the active end of the picker in a lowered position between the raised slider butts at heel height and the butts at normal cleared level until release is effected by the action of the cam 340.

The cam sequence of the machine will become apparent upon consideration of Figure 44, which shows an interior developed view of the cams cooperating with the sliders as well as illustrating the circumferential positions of other elements such as the cams for controlling the wrap yarn carriers and the narrowing and widening pickers.

Cooperating with the knitting butts 10 of the lower sliders are the forward stitch cam 342, the reverse stitch cam 344, the lower tip of which is relieved at 345 so that it will engage long butts only, and the top center cam 346. Cam 348 is in action during the formation of the heel and toe. It also helps in making a press-off draw thread, which, however, is not involved in the present invention and need not be described. Cam 350 is arranged to raise the lower sliders to clearing level as described hereafter. Cam 352 is arranged to lower the lower sliders for the press-off draw thread. Cam 354 is arranged to raise the lower sliders preparatory to the action of the cams 238 upon the saw tooth butts 14. Following the position of wrapping, there is a cam 356 arranged to raise the lower sliders preparatory to their approach to the stitch cams. Cams 349 and 358 are arranged to raise active lower long butt sliders to a clearing level during reverse rotation of the cylinders.

Arranged to cooperate with the transfer butts 12 of the lower sliders are cams 360 and 362, the latter being followed by cam 364 cooperating with the butts 10 to lower the sliders after a needle transferring operation.

The movable walls 22 and 24 are controlled by the action on their butts of a cam race 366, which includes a depression 368 for the purpose of moving the verge bits 24 downwardly at the time stitches are drawn by the needles in the upper cylinder, a rise 370 which, though it incidentally raises the verge bits, is primarily provided for the purpose of getting the walls 22 out of the way of the wrap yarn carriers, and a depression 372 arranged to cause the walls provided with the lower ends 30 to engage the wrap yarns to effect correct interlacing.

Arranged to act upon the upper transfer butts 18 of the upper sliders are cams 374 and 376,

which impart to the upper sliders a needle transferring wave, the dividing cam 361 operating in the usual fashion to release the sliders in both the upper and lower cylinders from the needles when transfer is to be effected. Following a transferring wave of the upper sliders, they are restored to normal clearing level by cam 376 from which level the cam 378, acting on their lower butts 16 raises the needles in the upper cylinder from their clearing level to the knitting level. An upper stitch cam 380 is provided followed by cams 386 and 388 arranged to effect clearing. Cams 382 and 384 are provided to lower long butt sliders for heel and toe knitting, the long butts being provided at the level 16.

A forward narrowing picker 390 and a reverse narrowing picker 392 are provided to cooperate with the long knitting butts at the level 10 of the lower sliders. The widening or lowering picker 310 has been referred to heretofore.

The arrangement of the slider butts for the purpose of securing proper transfer to form the welt and a 1 x 1 rib top followed by a broad rib leg and instep is fundamentally the same as described in the patent to Harold E. Houseman No. 2,170,078, dated August 22, 1939, and this may be referred to both for the arrangement of the transfer butts and the operations involved in the successive transferring actions. The present invention is not concerned with these features and it will suffice to begin the description of operation with the assumption that the division of the needles has been effected in the upper and lower cylinders to provide multiple needle panels in the lower cylinder to receive the wrap yarns. It may, however, be pointed out that, differing from the Houseman patent just referred to, the instep sliders in both cylinders are provided with short butts at 10 and 16, while the sole sliders in both cylinders are provided with long butts in the same positions.

In the formation of the leg, the lower sliders follow a path over the reverse stitch cam 344 and run down the center cam 346 and the forward stitch cam 342, taking the main yarn or yarns from the usual yarn feeding fingers, the position of which is indicated at 394. While only the active position of a yarn feeding finger is illustrated, it will be understood that the conventional Komet yarn changing mechanism is provided as illustrated, for example, in Bentley et al. Patent 1,838,651. Following the drawing of the yarn below the cam 342, the needles are raised by the action of cam 354, which positions them at a level for selection by the action of the cams 238 upon their lower butts 14. At this time the cams 238 are controlled by the trick wheel 248, the pin 284 on the lever 286 being in alignment with the notch 282, so that the pawl bar 256 is active for the purpose of advancing the trick wheel step by step on each rotation of the cylinders. By the selective action of the cams 238 on the butts 14, some of which butts are removed in the usual fashion to provide the proper selections, the needles 6 are either selectively raised to a level (the tuck level or slightly lower) to receive the wrap yarns, or remain at a lower level so as not to be engaged by the wrap yarns. As the lower sliders reach the cam 356, however, all of them are raised thereby to the clearing level, though, as will be pointed out hereafter, the rise to this level is not effective to cause the wrap yarns to drop below the latches, the wrap yarns being held high by the portion 188 of the horn so that only previous stitches are cleared.

The lower sliders are then in the proper path of approach to ride over the reverse stitch cam 344.

The wrapping operation will be made clear from a consideration of Figs. 12 and 24 to 36, inclusive. Selection of the warp yarn is effected by the control of the sliders 212 from the main cam drum of the machine through the plungers 218. The cams 204 are thus rendered selectively active and if an active cam is reached by a butt 13 of a sliding element 12, the corresponding wrap yarn finger or carrier is projected outwardly across the needle circle in advance of a series of needles in the lower cylinder and generally immediately following a group of needles in the upper cylinder. The outward projection of the lower end of the wrap yarn carrier occurs just prior to engagement with the abutment 224 and at a position following the completed rise due to a cam 238 of a lower slider which controls a needle supposed to take the wrap yarn. The condition immediately following the rocking outwardly of the lower end of the wrap yarn carrier is illustrated in Figures 24 and 25. The wrap yarn extends from the point at which it was last knit into the fabric and accordingly it is drawn about the horizontal portion of the wrap horn 186. As will be clear from Figure 24, the wrap yarn extends across the needle circle at a level below the upper ends of the upwardly selected needles but at a level above the hooks of the needles which were not selected.

The cams 204 and 222 may be arranged as indicated in Figure 44. The uppermost cam 204 is arranged to provide for the wrapping of wide panels and is sufficiently long to delay the return of a wrap yarn carrier by its spring until the last needle of a wide panel is passed by the carrier, the positive return cam, the upper one of the cams 222, being arranged for correspondingly delayed action. The two lower cams 204 and the lower return cam 222 act upon the carriers for more usual narrower multiple needle panels. The middle cam 204 acts on carriers associated with instep needles, while the lowermost cam 204 acts on carriers associated with sole needles. Thus, when the lowermost cam is withdrawn, the wrapping in the instep may be continued without wrapping in the sole.

As rotation proceeds, the wrap yarn carrier is retarded by the abutment 224, the spring which holds this abutment being sufficiently strong so that it will retain its fixed position while the long wrap yarn carrier flexes relative to the cylinders and away from the edge 98 of its corresponding fin 96, with which it was previously in contact and which guided its outward movement. Accordingly, as indicated in Figures 26 and 27, the wrap yarn is presented to the selected needles below the bills of their hooks.

The action of one of the cams 222 then returns the lower end of the wrap yarn carrier inwardly, releasing it from the abutment 224, whereupon it immediately snaps into its original position in contact with its fin 96, the latter condition being illustrated by the position existing in Figures 4, 28 and 29. During this inward movement of the lower end of the wrap yarn carrier, the yarn is cammed downwardly about the depending extension 87.

Up to this time the sliding wall elements 22 have been raised due to the action of the cam rise 370, so that they are out of position to interfere with the movements of the wrap yarn carrier. They are now lowered by the cam 372 at the time

of rise of the unselected needles due to the cam 356. As these unselected needles rise, the lower edges 30 of the movable walls engage the wrap yarn, as indicated in Figure 32, and due to the slope of these edges, the wrap yarn extending between the selected needles is cammed or held inwardly, so that the rising unselected needles will pass outside the wrap yarn to provide proper interlacing, as also indicated in Figure 32. At about the same time, the needles carrying the wrap yarn pass beyond the horizontal portion of the wrap horn 186 and reach the vertical portion 188, the upper edge of which is at a higher level than the upper surface of the horizontal portion. As a consequence of this, despite the rise of the wrapped needles over the cam 356 (which rise of wrapped needles begins later than the rise of the unwrapped needles due to the higher approaching level of the former), the wrap yarn is held high in the hooks and some degree of tension is imparted thereto which is thereafter maintained to insure that the wrap yarn takes a plating position in the stitches which are drawn. The needles accordingly rise to the clearing level without any possibility that the wrap yarn will get below the latches. The entry of the elements 22 between the needles serves to limit their flexure by the wrap yarns and thus they have an additional function in avoiding damage.

As the needles move down the cam 346, the wrap yarn is brought into contact with the plating cam slope 194, which overlaps the end 193 of the wrap horn. As indicated in the successive views, Figures 33, 34 and 35, this results in a substantial tensioning of the wrap yarn, resulting in plating when the wrap yarn, along with the main yarn taken at the main yarn feed, is drawn for the formation of stitches. Both the wrap yarn and the main yarn are thereafter held down by the sinkers as the needles rise to clear the latches.

The verge bits 24 with verge ends 32 function in conventional fashion to cause the proper formation of rib stitches by the needles in the upper cylinder.

In order to make possible the immediate wrapping of instep needles upon completion of the heel, the heel and toe of a stocking knit in the present machine are formed while holding the inactive instep needles at a low or welt level.

As mentioned above, the instep sliders are provided with short knitting butts 10 and 16, while the butts 10 and 16 of the sole sliders are long. In order to segregate the sole and instep sliders, the stitch cam 342 is withdrawn sufficiently to cause it to engage long butts only. This withdrawal is solely for the purpose of preventing the stitch cam from acting repeatedly on the short butt sliders during reciprocatory knitting in order to avoid undue tensioning of the loops held thereby. The cut-away lower end 345 of the reverse stitch cam 344 has the same object and makes it unnecessary to move this cam, the lower end 345 engaging the long butts but missing the short butts. Cam 348 is stepped in to engage long butts at 10 but miss short butts. Cam 349 is relieved at its upper end so that short butts may pass it while long butts will be raised during reverse reciprocations.

In the last rotation prior to the first reverse reciprocation in going on the heel, the short butt sliders will accordingly not be operated by cams 354 and 366, these cams being moved outwardly prior to the cam 362, which has its outward movement following the passage of the last short butt

sliders. Cams 348 and 382 come in to operate on long butts only. Cam 378 is withdrawn to allow long butts 16 to remain in the cleared level for latch protection during reciprocation while short butts 16 remain in the inactive welt race. The action involved is illustrated in Figure 45, in which the short butts are shown riding at the low inactive level, while the long butts pass through knitting waves in both directions of movement. The leading short butt slider is located at S, the figure representing conditions shortly prior to the end of the last rotation, at the end of which the trailing long butt slider will have risen over the top of cam 350.

Narrowing now takes place in conventional fashion, the leading long butt in each reciprocation being raised by one of the pickers 390 and 392 so that the needles engaged by long butt sliders are successively raised out of action. At this time the lowering picker 310 occupies an upper position above the level of the raised inactive long butts. The picking action in the first reverse reciprocation is indicated in Figure 46, and in the following first forward reciprocation in Figure 47.

When the narrowing is completed, and widening is to begin, the lowering picker 310 has its active end moved downwardly by the action of cam 318 on its tail portion. It is then in position to be engaged by the leading inactive long butts, which are to be picked downwardly.

A problem now arises, however, in the operation of the lowering picker, in that unless proper precautions were taken, it would be engaged by the leading inactive long butts at the ends of the long butt series of sliders in both directions of reciprocation rather than merely the leading inactive long butts following the group of lower active long butts. Accordingly, there comes into operation the lever 328. The initial lowering of the lowering picker by the cam 318 is caused to occur at the end of the stroke as the picker is reached by the central group of active long butt sliders. Accordingly, it will engage the two inactive long butts following this group and they will carry it forwardly so that, by the action of one of the cams 312, its inner end will move downwardly to lower these butts to the active level. When it is so lowered, the lever 328 will drop below its tail portion to hold it at a level between the active and inactive levels of the long butts. It is accordingly passed by the inactive long butts at the ends of the long butt series in both directions of reciprocation, being released to an upper level by the action of the cam 340, which rocks the lever 328 out from beneath the tail portion of the picker at the end of each reciprocation when the picker is reached by the central long butt sliders. Picking accordingly takes place in proper fashion despite the lower inactive positions of the short butts which, in conventional picking operations, ride at a high level and prevent the undesired action of the lowering picker. The widening accordingly proceeds with the lowering of two sliders and the raising of one in each reciprocation, the latter action being due to the continued action of the narrowing pickers. Figures 48 and 49 illustrate, respectively, the lowering picker actions in forward and reverse reciprocations, shortly following its release by the cam 340. Its latched inactive position is indicated in dotted lines in Figure 48.

In the restoration of the short butt sliders to operation following the completion of the heel, they ride upwardly over the cam 354, which is

moved inwardly to engage them so that, immediately upon coming into action, they will pass through selection to render them ready to take the wrap yarn.

During the formation of the leg, the cam 296 (Figure 20) acts to pull the lever 286 to the full line position of Figure 14 through the Bowden wire 292, so that, pin 284 being aligned with the notch 282, the pawl bar 256 will have full racking strokes. Lever 253 is released by its Bowden wire 302 since the lever actuating plunger 308 now rides on the surface of drum 182.

During the formation of the heel, in order not to interrupt the continuity of the wrap patterns from the front of the leg into the instep, the trick wheel is stopped from rotation, while at the same time the cams 238 are drawn outwardly so as not to engage the saw-tooth butts of the lower sliders. The former action occurs through the action of cam 298 and plunger 294 on the Bowden wire 292, which rocks the pin 284 to the right as viewed in Figure 14 to bring it out of alignment with the notch 282 in the laterally extending plate 280 carried by the pawl 256. Even though the cam 274 continues to rock the shaft 263, the pawl is held in a retracted position so that it cannot move forwardly to engage the next ratchet tooth. In order to render cams 238 inactive, the lever 253 is rocked by the action of cam 306 on plunger 308 through the Bowden wire 302 so as to cause the upturned portion 252 of the lever 253 to engage levers 242 to pull the cams outwardly.

In the formation of the foot, it is desirable to eliminate wrapping in the sole, confining this to the instep. This end is achieved by a control of the wrap yarn cams 204, as described above, in conjunction with a proper butt differentiation at 73 between the wrap yarn carriers which wrap instep needles and those which wrap sole needles.

During the formation of the foot cam 300 aligns pin 284 with notch 282 so that normal racking of the trick wheel continues. Cams 238 are again rendered active by release of lever 253 following passing of cam 306 beyond the follower lever controlling plunger 308.

In the formation of the toe, narrowing and widening are carried out as described above for the heel. During the formation of the toe, however, it is desirable to cause retiming of the trick wheel to set it for the beginning of the next stocking. For this purpose, while the cams 238 are again rendered inactive by the rocking of the lever 253, through the action of cam 304, the lever 286 is released by its Bowden wire 292 (by the dropping of the cam follower lever of plunger 294 off cam 309) so that, if not otherwise prevented, it could move to the left-hand dotted line position illustrated in Figure 14, so that again the pawl 256 would be rendered inoperative. This, however, is prevented by the presence of butts acting on the follower end 244 of the lever until the trick wheel turns to present to the follower a trick having a butt missing at the level of the follower end 244. At such time the pin 284 will rock to the left and, accordingly, further advance of the trick wheel will cease. The conditions so attained then prevail until the knitting of the leg of a subsequent stocking is started.

The purpose of the heel take-up is to insure that the tension throughout the circumference of the stocking is even during the knitting of the foot after the formation of the heel. The usual roller take-up (not shown) is provided, but after the formation of the heel, because of the loose heel pocket, its pull is exerted primarily on the

instep and not through the heel pocket to the sole. By the action of the fingers 106 in the heel pocket, however, due to the weight 144, a tension is imparted to the sole as indicated in Figure 40, so that the stitches are properly formed throughout the circumference of the foot. A similar action occurs when the take-up acts upon the toe, assisting in proper make up and welt formation. Cams 178 and 180 raise the take-up prior to these operations and then release it for action under its weight.

Due to the fact that the instep needles are riding low during the formation of the heel and toe special provision must be made in the machine to prevent the yarn from being retained, with the formation of loops, under the nebs of sinkers during the passage of the idle needles in reciprocation. In machines in which the instep needles are raised to an inactive level during reciprocation, it has been customary to provide devices known as bluffs to overlap the sinker nebs to prevent entrapment of the yarn, as, for example, illustrated in Bentley et al. Patent 1,986,317 or Houseman Patent 2,264,977, these bluffs being raised by the inactive sliders. In the present machine there is provided an extra outward wave of the sinkers in the center of the usual wave in which the sinkers pull out.

This is accomplished by providing at 400 (Figure 51) between the cams 52 and 53 in a circumferential position corresponding to the heel yarn finger 492 a special wave to cause the sinker neb to move outwardly beyond the usual wave. The sinker neb then follows a path such as indicated at 404 in Figure 50. During reciprocation, after the active needles have passed the yarn finger and the inactive needles are passing it, the yarn may get beneath the nebs of the sinkers associated with the inactive needles. This entrapped portion of the yarn must be retrieved from beneath the nebs on the return stroke, and this is accomplished when the sinkers are moved outwardly at 400, directly below the yarn finger, sufficiently to release the entrapped yarn which is then drawn back through the yarn finger by the take-up. Thus there is avoided the formation of a yarn loop at the gore. The added wave does not interfere with the normal functioning of the sinkers.

50 A stocking formed by the machine described is illustrated in Figure 21. This comprises a 1 x 1 rib top A integrally followed by a leg having broad ribs B and wrap patterns C in the panels between the ribs. The broad ribs in the rear of the leg terminate at D above the heel E, while those at the front of the leg continue through the instep at F; the sole G being plain. A plain ring toe H follows the foot and precedes the toe I, finished off with loopers rounds in the 55 unusual fashion. In general, the stocking is of known type and the portions the formation of which has not been specifically described are knit in conventional fashion.

Wrap patterns formed between broad ribs are indicated in Figures 42 and 43. As will be evident, these may take a wide variety of forms depending solely upon the set up of wrap yarn carriers and needle selection. Exceptionally wide designs such as in the left hand panel of Figure 43 may be produced by the use of the uppermost cams 204 and 222 by which the outer position of a wrap yarn carrier is prolonged, while for the narrower designs, the wrap yarn carriers may be returned more quickly by the use

of the lower cams of these sets, to avoid conflict with the rib needles.

The pattern control devices herein disclosed are claimed in Patent 2,460,487, issued February 1, 1949.

What I claim and desire to protect by Letters Patent is:

1. A knitting machine comprising superposed rotary needle cylinders, needles carried by said cylinders, means located within one of the cylinders carrying a wrap yarn for presentation to needles, a carrier for said means rotating with the cylinders, a stationary support secured to the machine frame within said cylinder and extending between said cylinder and said wrap yarn carrying means, a wrap horn carried by said support about which horn the wrap yarn is drawn during a wrapping operation, and separate driving gearing for said cylinder and for said carrier.

2. A knitting machine comprising superposed rotary needle cylinders, needles carried by said cylinders, means located within one of the cylinders carrying a wrap yarn for presentation to needles, a carrier for said means rotating with the cylinder, a stationary bearing for said carrier located adjacent to the end of said cylinder remote from the needle-carrying end thereof, a stationary support secured to said bearing, and a wrap horn carried by said support about which horn the wrap yarn is drawn during a wrapping operation.

3. A knitting machine comprising superposed needle cylinders, needles carried by said cylinders, means carrying a wrap yarn for presentation to needles, a cylinder within one of said needle cylinders, and a plating cam carried by the last mentioned cylinder and arranged to engage a wrap yarn following its presentation to the needles.

4. A knitting machine comprising superposed needle cylinders, needles carried by said cylinders, means carrying a wrap yarn for presentation to needles, a support within one of said needle cylinders, and a plating cam carried by the support and arranged to engage a wrap yarn following its presentation to the needles.

5. A knitting machine comprising superposed needle cylinders, needles carried by said cylinders, means carrying a wrap yarn for presentation to needles, a support within one of said needle cylinders, and a plating cam carried by the support inside the needle circle and arranged to engage a wrap yarn following its presentation to the needles.

6. A knitting machine comprising superposed needle cylinders, needles carried by said cylinders, means carrying a wrap yarn for presentation to needles, a support within one of said needle cylinders, a wrap horn carried by said support about which horn the wrap yarn is drawn during a wrapping operation, and a plating cam carried by the support and arranged to engage a wrap yarn following its presentation to the needles.

7. A knitting machine comprising superposed needle cylinders, needles carried by said cylinders, means carrying a wrap yarn for presentation to needles, a support within one of said needle cylinders, a wrap horn carried by said support about which horn the wrap yarn is drawn during a wrapping operation, and a plating cam carried by the support and arranged to engage a wrap yarn as it leaves the free end of the wrap horn.

8. A knitting machine comprising superposed needle cylinders, needles carried by said cylinders, means carrying a wrap yarn for presentation to needles, a support within one of said needle cylinders, a wrap horn carried by said support about which horn the wrap yarn is drawn during a wrapping operation, and a plating cam carried by the support and arranged to engage a wrap yarn as it leaves the free end of the wrap horn overlapping the plating cam.

9. A knitting machine comprising a needle cylinder, needles carried by the cylinder, means carrying a wrap yarn for presentation to needles, a wrap horn about which the wrap yarn is drawn during a wrapping operation, and a plating cam arranged to engage a wrap yarn following its presentation to the needles.

10. A knitting machine comprising a needle cylinder, needles carried by the cylinder, means carrying a wrap yarn for presentation to needles, a wrap horn about which the wrap yarn is drawn during a wrapping operation, and a plating cam arranged to engage a wrap yarn as it leaves the free end of the wrap horn.

11. A knitting machine comprising a needle cylinder, needles carried by the cylinder, means carrying a wrap yarn for presentation to needles, a wrap horn about which the wrap yarn is drawn during a wrapping operation, and a plating cam arranged to engage a wrap yarn as it leaves the free end of the wrap horn, the free end of the wrap horn overlapping the plating cam.

12. A knitting machine comprising superposed needle cylinders, needles carried by said cylinders, means carrying a wrap yarn for presentation to needles, and members slidably mounted in one cylinder for engagement with wrap yarn extending between needles in the other cylinder.

13. A knitting machine comprising superposed needle cylinders, needles carried by said cylinders, means carrying a wrap yarn for presentation to needles, and members slidably mounted in one cylinder for engagement with wrap yarn extending between needles in the other cylinder, and constructed and arranged to hold the wrap yarn inwardly of unwrapped needles moving to join the path of wrapped needles.

14. A knitting machine comprising superposed needle cylinders, needles carried by said cylinders, means carrying a wrap yarn for presentation to needles, and members slidably mounted in one cylinder for engagement with wrap yarn extending between needles in the other cylinder, said members providing walls defining needle slots in the first mentioned cylinder.

15. A knitting machine comprising superposed needle cylinders, needles carried by said cylinders, means carrying a wrap yarn for presentation to needles, members slidably mounted in one cylinder for engagement with wrap yarn extending between needles in the other cylinder, said members being provided with butts, and cams engageable with the butts for controlling movements of said members.

16. A knitting machine comprising superposed needle cylinders, needles carried by said cylinders, means carrying a wrap yarn for presentation to needles, members slidably mounted in one cylinder for engagement with wrap yarn extending between needles in the other cylinder, and other members slidably mounted in the first mentioned cylinder for engaging yarn extending between needles in the first mentioned cylinder.

17. A knitting machine comprising superposed needle cylinders, needles carried by said cylinders, said members slidably mounted in one cylinder for engagement with yarn extending between needles in said cylinder, said members providing walls defining needle slots in said cylinder.

18. A knitting machine comprising superposed needle cylinders, needles carried by said cylinders, members slidably mounted in one cylinder for engagement with yarn extending between needles in said cylinder, said members providing walls defining needle slots in said cylinder, said members being provided with butts, and cams engageable with the butts for controlling movements of said members.

19. A knitting machine comprising superposed rotating needle cylinders, means carrying a wrap yarn for presentation to needles, means supporting said carrying means within the upper cylinder for rotation therewith and mounting means for said supporting means, the mounting means comprising an axially movable and rotatable member carrying said supporting means and constructed and arranged that the supporting means with the wrap yarn carrying means may be lifted from the upper cylinder and laterally swung to, and held in, an accessible location.

20. A knitting machine comprising superposed rotating needle cylinders, means carrying a wrap yarn for presentation to needles, means supporting said carrying means within the upper cylinder for rotation therewith, and mounting means for said supporting means, the mounting means comprising an axially movable and rotatable member provided with a bearing carrying said supporting means and constructed and arranged that the supporting means with the wrap yarn carrying means may be lifted from the upper cylinder and laterally swung to, and held in, an accessible location.

21. A knitting machine comprising superposed rotating needle cylinders, means carrying a wrap yarn for presentation to needles, means supporting said carrying means within the upper cylinder for rotation therewith, a fixed bearing for said supporting means located adjacent to the upper end of the upper cylinder, and mounting means for said supporting means, the mounting means comprising an axially movable and rotatable member carrying said supporting means and constructed and arranged that the supporting means with the wrap yarn carrying means be lifted from the upper cylinder and said fixed bearing and laterally swung to, and held in, an accessible location.

22. A knitting machine comprising superposed rotating needle cylinders, means carrying a wrap yarn for presentation to needles, means supporting said carrying means within the upper cylinder for rotation therewith, a fixed bearing for said supporting means located adjacent to the upper end of the upper cylinder, and mounting means for said supporting means, the mounting means comprising an axially movable and rotatable member provided with a bearing carrying said supporting means and constructed and arranged that the supporting means with the wrap yarn carrying means may be lifted from the upper cylinder and said fixed bearing and laterally swung to, and held in, an accessible location.

23. A knitting machine comprising superposed rotating needle cylinders, means carrying a wrap yarn for presentation to needles, means supporting said carrying means within the upper cylinder for rotation therewith, and mounting means

for said supporting means, the mounting means comprising an axially movable and rotatable member carrying said supporting means and constructed and arranged that the supporting means with the wrap yarn carrying means may be lifted from the upper cylinder and laterally swung to, and held in, an accessible location, and means for guiding said supporting means to proper position when the wrap yarn carrying means is re-located in the upper cylinder.

24. A knitting machine comprising superposed needle cylinders, needles carried by said cylinders, means carrying a wrap yarn for presentation to needles, and blades slidably mounted in one cylinder for projection between wrapped needles in the other cylinder to limit movement of the wrap yarn.

25. For a knitting machine of the opposed needle bed type, a needle bed having trick walls 20 constituted by individually-slidable blades capable of projection and retraction at the margin of the bed.

26. A knitting machine comprising a needle cylinder, needles carried by said cylinder, a flexible wrap yarn carrier, means for supporting the wrap yarn carrier at a portion thereof remote from its yarn-carrying end, means adjacent to the needles engaging the wrap yarn carrier to align it circumferentially with the needles, said 25 engagement being due to the flexibility of the carrier from its point of support to its yarn carrying end, and an abutment for engagement with the carrier to flex it away from said engaging means and to provide a wrapping movement 30 of the carrier relative to the needles to effect wrapping of a plurality thereof.

27. In a knitting machine of the opposed needle bed type, a needle bed having a plurality of grooves, and a blade longitudinally slidably in 40 each such groove but standing proud thereof whereby the space between successive blades forms a needle trick the walls of which are constituted by the blades themselves, means for projecting said blades along their grooves one after 45 another towards the other bed and means for retracting them one after another away from the other bed.

28. A knitting machine of the opposed needle bed type, having wrap-thread mechanism including at least one wrap-thread finger movable at 50 a wrapping station between the adjacent margins of the two beds to supply wrap thread to at least one needle, needle-trick walls, in at least one bed, constituted by individually-slidable blades capable of projection and retraction at the margin 55 of the bed, and operating means for retracting them at the wrapping station to provide room for the movements of the wrap finger.

29. A knitting machine of the opposed needle 60 cylinder type, having wrap-thread mechanism including at least one wrap-thread finger movable between the two sets of needles, at a wrapping station, across the needle line and along said line to supply wrap thread to at least one needle, needle-trick walls in at least one bed constituted by individually-slidable blades capable of projection at the margin of the bed towards the other bed, and blade operating means for retracting said blades at the wrapping station to afford room for the movements of the wrap finger and for thereafter projecting them.

30. A knitting machine of the opposed needle bed type, having at least one needle bed having a plurality of grooves, a blade slidably longitudinally in each such groove but standing proud

thereof whereby the space between successive grooves forms a needle trick the walls of which are constituted by the blades themselves which blades have ends over which the knitted loops are drawn, needle-operating means for said bed including a stitch cam, and blade-operating means for sliding said blades in their grooves and including means for projecting them in the vicinity of the stitch-drawing point to cooperate with the stitch cam in drawing loops and for retracting them at a wrapping station, and means for supplying wrap threads to the needles at the wrapping station.

31. In a knitting machine of the opposed needle cylinder type having at least one yarn feeder movable, at a feeding station, between the margins of the two beds and across the line of needles, the combination of a needle cylinder having trick walls constituted by individually-slidable blades capable of projection and retraction at the margin of said cylinder, and blade-operating means for projecting said blades towards the other cylinder butt for retracting them at the said station.

32. In a machine according to claim 31, the combination with a needle stitch cam for retracting the needles into first mentioned needle cylinder at a stitch-drawing point, of means, in the blade-operating means, for projecting the blades at the stitch-drawing point to cooperate with the retracting needles in drawing stitches.

33. In a circular knitting machine of the superimposed needle cylinder type, having wrap-thread mechanism comprising a plurality of wrap-thread fingers suspended within the upper needle cylinder and each having a thread-guiding lower end, and means for effecting a selection from among the fingers and for operating each selected finger, at a wrapping station, to move its thread-guiding end outwards across the needle circle, sideways past at least one needle, and inwards across the needle circle, whereby its thread is wrapped round at least one needle; the combination of an upper needle cylinder having needle trick walls constituted by individually-slidable blades capable of projection and retraction at the lower margin of said cylinder, and blade-operating means for projecting said blades towards the lower cylinder butt for retracting them at the wrapping station to afford room for the aforesaid movements of the ends of the wrap fingers.

34. In a circular knitting machine of the superimposed rotary needle cylinder type, having wrap-thread mechanism comprising at least one wrap thread finger suspended at a stationary location within the upper needle cylinder and having a lower thread-guiding end capable of making thread-wrapping movements at a stationary wrapping station, said movements comprising movement outwards across the needle circle between the two cylinders, sideways movement in relation to at least one needle, and retraction into the interior of the needle circle; the combination of a needle cylinder having needle trick walls constituted by individually slidable blades mounted in the periphery of that cylinder for projection of their ends at the margin of the cylinder towards the other cylinder, and blade-operating means for maintaining said blades projected throughout the major portion of the circle butt for retracting them one after another as they approach the wrapping station.

35. A knitting machine comprising superimposed cylinders for the reception of needles

carried by said cylinders, and members slidably mounted in one cylinder for engagement with yarn extending between needles in said cylinder, said members providing walls defining needle slots in said cylinder.

36. A knitting machine comprising a stationary frame, superposed rotary needle cylinders, needles carried by said cylinders, means located within one of the cylinders carrying a wrap yarn for presentation to needles, a carrier for said means rotating with the cylinders, and a stationary cylinder secured to said frame and located between the last mentioned needle cylinder and said means.

37. A knitting machine comprising superposed rotary needle cylinders having adjacent inner ends, needles carried by said cylinders, means located within one of the cylinders carrying a wrap yarn for presentation to needles, a carrier for said means rotating with the cylinders, and a stationary cylinder extending from the outer end of the last mentioned needle cylinder to a point adjacent to the inner end thereof between said needle cylinder and said means.

38. A knitting machine comprising a stationary frame, superposed rotary needle cylinders, needles carried by said cylinders, means located within one of the cylinders carrying a wrap yarn for presentation to needles, a carrier for said means rotating with the cylinders, a stationary cylinder secured to said frame and located between the last mentioned needle cylinder and said means, and a wrap horn carried by said stationary cylinder about which horn the wrap yarn is drawn during a wrapping operation.

39. A knitting machine comprising superposed rotary needle cylinders having adjacent inner ends, needles carried by said cylinders, means located within one of the cylinders carrying a wrap yarn for presentation to needles, a carrier for said means rotating with the cylinders, a stationary cylinder extending from the outer end of the last mentioned needle cylinder to a point adjacent to the inner end thereof between said needle cylinder and said means, and a wrap horn carried by said stationary cylinder about which horn the wrap yarn is drawn during a wrapping operation.

PAUL W. BRISTOW.
